UNITED STATES PATENT OFFICE

WILLIAM BLANKNER, OF MIAMI, FLORIDA

KNIFE SHARPENING DEVICE

Application filed March 16, 1927. Serial No. 175,680.

This invention relates to sharpening devices and more particularly to a device adapted to sharpen the cutting edge of knives or other articles of cutlery, which device is simple in construction and inexpensive to manufacture but exceptionally efficient in operation.

One of the objects of the invention is to provide a sharpening device, the abrasive members of which are adapted to adjust themselves to conform to the flat surfaces of the cutting edge irrespective of the vertical position of the knife between the said members, thereby causing the knife to be sharpened along its true cutting edge.

A further object of the invention is to provide means for adjusting the angular relationship of the abrading members so that the cutting edge of the knife may be sharpened irrespective of the angle of the cutting edge.

A further object of the invention is to provide means for independently adjusting the angular position of the abrading members with respect to each other and the cutting edge of the knife to be sharpened so that upon engagement of the knife with the abrading members the said members will automatically adjust themselves to the angle corresponding to the bevels of the cutting edge.

Another object of the present invention is to provide means whereby one of the abrading members can be reciprocated so that the sharpening device is capable of sharpening knives of different thicknesses and sizes.

As a final object of the invention, means are provided whereby upon the reciprocation of one of the abrading members oil is pumped from a suitable receptacle and deposited upon the sharpening edge of the abrading members to thereby materially assist in the sharpening of the knives or other articles to be sharpened.

With the objects above indicated and other objects hereinafter explained in view, my invention consists in the construction and combination of elements hereinafter described and claimed.

Referring to the drawing:

Fig. 1 is a side elevational view of a device embodying my invention.

Fig. 2 is a top plan view of the device shown in Fig. 1 with the top portion of the frame removed.

Fig. 3 is a vertical cross-sectional view taken on line 3—3 of Fig. 1, and showing the construction of the carriage.

In the drawing, the frame 10 comprises a bottom plate 11, upwardly extending end members 12 and 13 formed integral with the base plate 11, and the upper portion of the end member 13 is provided with an inwardly extending top plate 14 formed integral therewith and extending inwardly to substantially the center of the frame 10. This frame 10 is supported by a plurality of legs 15 disposed at the four corners of the base plate 11 and connected thereto by any suitable means. The base plate 11 is provided with a pair of parallelly extending guides 16 upon the upper surface thereof while the top plate 14 is provided with a pair of parallelly extending guides 17 upon the under surface thereof, the guides 16 and 17 being in vertical alignment and formed integral with the base plate 11 and top 14 respectively or secured in any other suitable manner.

A carriage 18 is positioned between the top plate 14 and the base plate 11, and is provided with a horizontal top plate 19 and a horizontal bottom plate 20. The horizontal top plate 19 is provided with a pair of upwardly extending lugs 21 adapted to reciprocate within one of the guides 17 of the top member 14. The bottom plate 20 of the carriage 18 is constructed in a manner similar to top plate 19 and is provided with a pair of integrally formed depending lugs 23 adapted to freely reciprocate within one of the guides 16 upon the base plate 11, while a second pair of depending lugs 24 extend parallel with and are spaced apart from the lugs 23 so as to freely reciprocate within the opposite guide 16. From the foregoing description it will be readily seen that the carriage 18 is free to reciprocate within the guides 16 upon the bottom plate 11 and within

the guides 17 upon the top plate 14. A plurality of supporting members 25 are bolted at 26 and 27 to the ends of the plates 19 and 20 respectively and extend at an incline due to 5 the fact that the plate 19 is substantially shorter than the plate 20. The angle of these supporting members should be substantially one-half the total adjustment of the adjacent abrading member, as will be hereinafter 10 described.

Each of the supporting members 25 is provided at its lower end with a foot or lateral extension 28 and upon its opposite edges with outwardly extending parallel clips 29 15 which are adapted to support therebetween an abrading member 30. The lower inner edge of the abrading member 30 is rounded off, as indicated at 31, and the end of the member is adapted to freely rest upon the 20 lateral extension 28. The upper end of the abrading member 30 is spaced from the supporting member 25 by a spring 32, which spring permits the abrading member 30 to adjust itself to the angle or bevel of the cutting edge of the knife to be sharpened. This 25 adjustment is made possible by the fact that the lower end of the abrading member 30 is in no manner secured to the supporting member 25, the abrading member 30 being free 30 to move about the rounded edge 31 in engagement with the supporting member 25. The opposite abrading members 32, a plurality of which are herein shown, are each supported by a supporting member 33 similar to the 35 supporting member 25, the lower end of each supporting member 33 being provided with a lateral extension or foot 34 and with parallelly extending side slips 35 between which an abrading member 32 is supported. 40 The supporting members 33 are each bolted or otherwise secured to a plate 36 which has formed at its lower outer edge an ear 37 which is pivoted at 38 to the extension 39 formed integrally upon the upper 45 surface of the base member 11. The upper end of the abrading member 32 is spaced from the supporting member 33 by a spring 40 similar to spring 32, which separates the abrading member 30 from the supporting 50 member 25, and the lower inner edge of the abrading member 32 is rounded at 41 to permit the abrading member to readily adjust itself within the supporting member 32 to the bevel of the cutting edge of the knife. 55 It is desirable to adjust the angular position of the abrading member 32 on account of the different bevels of the cutting edges of the knives to be sharpened, and I therefore provide a screw-threaded rod 42 adapted 60 to engage a screw-threaded opening 43 provided in the upper portion of the end member 12, the inner end of the rod being universally connected at 44 to an extension 45 formed integrally upon the rear portion of 65 the plate 36. The forward end of the rod

42 is provided with a hand wheel 46 keyed or otherwise secured thereto, and upon rotation of the hand wheel it will be readily seen that the angular position of the plate 36 and, consequently, of the abrading members 32 is varied, depending upon the direction of rotation of the hand wheel 46. An indicator 70 may be employed to determine the angular position of the plate 36, and I therefore provide an upstanding arm 47 bolted to the upper portion of the end member 12 and having a graduated portion 48 graduated in degrees. At the upper portion of the plate 36 an indicator arm 49 is bolted or otherwise secured thereto, the point of the indicator 75 arm cooperating with the graduations upon the extension 48.

To maintain a tension or pressure upon the knife or other implement to be sharpened the reciprocating carriage 18 is constantly held inwardly by means of a plurality of springs 50. These springs, of which four in number are herein illustrated, surround a plurality of horizontally extending rods 51 which have one end screw-threaded into suitable openings 52 in the end plate 13, while the inner end slidably extends through suitable openings in the carriage 18. It will be noticed that the springs 50 are adapted to abut at one end with the inner surface of the end plate 13 while the opposite end abuts with a portion of the carriage 18. These springs maintain the carriage in its innermost position, and when the knife or other implement to be sharpened is forced downwardly between the abrading members 30 and 32, the carriage 18 is moved outwardly against the tension of the springs 50, and upon removal of the knife the springs 50 will return the carriage to its normal inward position. It will, therefore, be noted that a tension or pressure is continually maintained upon the knife while the same is being 100 sharpened.

In sharpening devices it is desirable to 110 provide some means for supplying oil to the sharpening edges of the abrading members, and in the present instance I have provided a receptacle 53 adapted to contain the oil and bolted to the under side of the base plate 11. Within the receptacle is mounted an ordinary cylinder 54 in which reciprocates a piston 115 or plunger 55. This plunger is connected at 56 to a depending arm 57 bolted or otherwise secured to the carriage 18, which arm extends through a suitable slot 58 provided in the base plate 11. The lower portion of the cylinder 54 has connected thereto a pipe 59 the free 120 end of which is adapted to be positioned within the oil contained in the receptacle 53. At the upper portion of the cylinder 54 pipe lines 60 and 61 communicate through tubing 62 and 63 respectively with the faces 125 of the abrading members. The upper end of the tubing 62 is connected to the end of a 130

forked member 64, the free ends of which correspond to the number of abrading members 32 and are held in engagement with the sharpening surfaces of the abrading members 5 by means of a plurality of clips 65. The upper end of the tubing 63 is connected to one end of a forked member 66, the free ends of which correspond to the number of abrading members 30 and are held in contact with 10 the sharpening faces of the abrading members by means of a plurality of clips 67. It will readily be seen that upon reciprocation of the carriage 18 the piston 55 is reciprocated within the cylinder 54 and upon its 15 rearward movement the oil is drawn through the pipe 59 into the cylinder 54, but upon its forward movement the oil within the cylinder is forced upwardly through the pipes 60 and 61 and onto the sharpening edges of the 20 abrading members 30 and 32.

In the operation of the sharpening device, the plate 36 is adjusted to the desired angle by rotation of the hand wheel 46 in the proper direction, which angle should substantially correspond to the bevel of the cutting edge of the knife. The knife is then positioned with the cutting edge extending downwardly between the abrading members 30 and 32 and downward movement causes 25 the abrading members 30 and 32 to adjust themselves to the bevel of the cutting edge of the knife due to the fact that these abrading members 30 and 32 are freely carried by the supporting members 25 and 33. They 30 will adjust themselves to the bevel of the cutting edge as the knife is moved inwardly and downwardly during the sharpening operation. The farther downwardly the knife is moved the farther outwardly the carriage 18 35 is moved, and at the same time sufficient pressure is maintained through the springs 20 upon the cutting edge of the knife to cause the same to be completely sharpened. Each time the knife is moved forwardly and downwardly during the sharpening operation the carriage is moved outwardly, and each time the knife is moved backwardly and outwardly the carriage 18 is permitted to move inwardly, thereby causing the oil to be pumped 40 to the sharpening edges of the abrading members. It will be noted that the abrading members 30 and 32 are staggered with respect to each other and substantially overlap at their lower ends so that the sharpening 45 of the knife or other implement can be effected substantially throughout the entire sharpening surface of the abrading members.

When the bevel of the abrasive member 32 is changed by rotation of the hand wheel 46, it may be desirable to position the device so that the angle between the abrasive members 30 and 32 as related to a line perpendicular through the apex of the angle is the same. Therefore the frame 10 may be pivoted at 68 to the legs 15 and the opposite

legs 15 can have a lug 69 formed integral therewith and extend inwardly with a tapped opening 70 extending through said lugs 69. The base plate 11 supports a rotatable bolt 71 provided with shoulders 72 to prevent longitudinal movement of the bolt and the lower end of the latter is screw-threaded and engages with the tapped opening 70 in the lugs 69.

It will, therefore, be seen that the horizontal position of the frame 10 can be changed by turning the bolt 71 which thereby centralizes the abrasive members 30 and 32 with respect to a line perpendicular with the apex of the angle between the members. This adjustment permits the knife being sharpened to engage the abrasive members in a vertical position and thereby produce an even edge upon the knife.

While I have described the preferred construction of the device embodying my invention, it is to be understood that various changes in the construction and arrangement of the different elements can be resorted to without departing from the spirit of the invention as defined in the appended claims.

Having thus described my invention, I claim:

1. A knife sharpening device comprising two sets of abrading members positioned in staggered relation and extending upwardly at a diverging angle, means for supporting each set of members, one of said supporting means being angularly adjustable manually, and means for causing said members to adjust themselves to the different bevels of cutting edges of implements upon engagement therewith.

2. A knife sharpening device comprising two sets of abrading members positioned in staggered relation and extending upwardly at a diverging angle, means for supporting each set of members, one of said supporting means being movable in the same plane toward and away from the other of said supporting means while the other of said supporting means is angularly adjustable, and means for causing said members to adjust themselves to the different bevels of cutting edges of implements upon engagement therewith.

3. A knife sharpening device comprising two sets of abrading members positioned in staggered relation and extending upwardly at a diverging angle, means for supporting each set of members, one of said supporting means being angularly adjustable, an indicating means associated with said supporting means adapted to indicate the angular position of said adjustable supporting means, and means for causing said members to adjust themselves to the different bevels of cutting edges of implements upon engagement therewith.

4. A knife sharpening device comprising

- two sets of abrading members positioned in staggered relation and extending upwardly at a diverging angle, means for supporting each set of members, one of said supporting means being angularly adjustable, means for adjusting said supporting means, and means for causing said members to adjust themselves to the different bevels of cutting edges of implements upon engagement therewith. 70
- 10 5. A knife sharpening device comprising two sets of abrading members positioned in staggered relation and extending upwardly at a diverging angle, means for supporting each set of members, one of said supporting means being movable in the same plane toward and away from the other of said supporting means, means for guiding said movable supporting means, and means for causing said members to adjust themselves with respect to said supporting means to the different bevels of cutting edges of implements upon engagement therewith. 75
- 15 6. A knife sharpening device comprising two sets of abrading members positioned in staggered relation and extending upwardly at a divergent angle, means for supporting each set of members, one of said supporting means being movable toward and away from the other of said supporting means, means for maintaining said movable supporting means in its normal inward position, and means for causing said members to adjust themselves with respect to said supporting means to the different bevels of cutting edges of implements upon engagement therewith. 80
- 20 7. In a knife sharpening device and the like, the combination of a frame, a member pivotally connected to said frame, a plurality of abrading members supported by said member, a carriage slidably mounted on said frame, and a plurality of abrading members supported by said carriage, each plurality of abrading members being positioned in staggered relation and at a converging angle with respect to the other plurality of abrading members. 85
- 25 8. In a knife sharpening device and the like, the combination of a frame, a member pivotally connected to said frame, means for adjusting the angular position of said member, a plurality of abrading members supported by said member, a carriage slidably mounted on said frame, and a plurality of abrading members supported by said carriage, each plurality of abrading members being positioned in staggered relation and at a converging angle with respect to the other plurality of abrading members. 90
- 30 9. In a knife sharpening device and the like, the combination of a frame, a plate pivotally connected to said frame, supporting members fixed to said plate, abrading members carried by said supporting members, resilient means positioned between said supporting members and said abrading mem- 95
- 35 bers, a carriage slidably mounted on said frame, supporting members connected to said carriage, abrading members carried by said latter supporting members, and resilient means positioned between the second abrading members and their supporting members, the first set of abrading members being staggered and at a converging angle with respect to the other set of abrading members. 100
